UNITED STATES PATENT OFFICE.

ARTHUR E. BENSON, OF AGRICULTURAL COLLEGE, MISSISSIPPI, ASSIGNOR
TO DRAPER COMPANY, OF HOPEDALE, MASSACHUSETTS, A CORPORA-
TION OF MAINE.

FILLING-DETECTING MECHANISM FOR LOOMS.

No. 823,251.

Specification of Letters Patent.

Patented June 12, 1906.

Application filed September 28, 1905. Serial No. 280,445.

To all whom it may concern:

Be it known that I, ARTHUR E. BENSON, a citizen of the United States, residing at Agricultural College, county of Oktibbeha, State 5 of Mississippi, have invented an Improvement in Filling-Detecting Mechanism for Looms, of which the following description, in connection with the accompanying drawings, is a specification, like numerals on the drawings representing like parts.

This invention relates to the filling-detecting mechanism of a loom whereby the presence or absence of the running filling is detected; and it has for its object the production 15 of means whereby the filling-fork is positively restored to detecting position if necessary, the rebounding tendency of the fork also being diminished.

The various novel features of my invention will be fully described in the subjoined specification, and particularly pointed out in the following claims.

Figure 1 is a side elevation of so much of the filling-detecting mechanism of a loom as 25 pertains to my invention with one form of the invention embodied therein, the nearer side of the fork support or slide being broken out, the parts being shown in detecting position; and Fig. 2 is a similar view, but showing the 30 parts in their relative position after the detecting action of the fork.

The stand or guide 1, the fork support or slide 2, longitudinally movable therein upon detection of filling failure, the cross-bar or 35 hook-support 3, and weft hammer or vibrator 4 may be and are all of well-known construction and operate as usual.

Upon a transverse fulerum-pin 5 at the rear end of the fork-slide the filling-fork is 40 mounted, said fork comprising a body 6, tines 7 to engage the filling when present, and a tail 8, and in accordance with my present invention I have provided the body with a depending extension 9. This extension 45 tends to lower the center of gravity of the fork as a whole, and thereby causes the fork to be more in a condition of stable or balanced equilibrium when in detecting position, as shown in Fig. 1. The resistance of 50 the fork to tilting movement by engagement with the filling is thereby diminished, and the

filling is in consequence subjected to less strain.

As will appear hereinafter, the extension 9 has another function—in assisting the return 55 of the fork to detecting position by a positive action.

The hook 10, pivotally connected with the weft-hammer 4 at 11, is of peculiar construction in that it has an enlarged or cam portion 60 12 on its under side adjacent its free end, and between the upturned shoulder 13 and the tip of the hook the latter is built up to form a second cam-surface 14.

When the weft-hammer is back, (see Fig. 65 1,) the cam portion 12 is beyond the support 3, and the hook is in its lowest position, the fork-tail 8 resting on the top of the hook in front of its shoulder 13, the fork then being in detecting position, the tip of the hook at such 70 time being quite close to the extension 9.

As the lay beats up on the detecting-pick the weft-hammer moves forward, and the tip of the hook is moved forward away from the extension 9, so as to permit the fork to be 75 tilted if the filling is present to lift the tail 8 above the hook-shoulder. At the same time the cam portion 12 rides up on the support 3, lifting the hook, and thereby moving its tip upward; the forward and upward movement of the tip permitting a free tilting of 80 the filling-fork. If the filling is absent, the hook-shoulder and fork-tail coöperate, as usual, and the fork-slide 2 is moved outward to effect a change in the operation of the 85 loom. Should the fork be tilted, however, the lifting of the hook by the cam 12 raises the cam-surface 14 to such a height that when the return movement of the fork takes place its tail 8 can move down a very 90 short distance before it engages the cam-surface 14. This distance may be so slight that almost no descent of the tail takes place; but even if the fork be tilted into dotted-line position, Fig. 2, the fall of the tail is so much 95 diminished that practically no rebound will follow, and the fork will remain in the full-line position until the inward stroke of the weft-hammer permits the hook to drop, and the tail then descends in front of the hook-shoulder 13. As the hook moves back its tip 100 will engage the extension 9 should the fork

for any reason fail to return promptly to normal position, and the slight blow struck upon the extension promptly and positively insures the return of the fork to detecting position.

5 My invention is not restricted to the precise construction herein shown and described which embodies one practical form only of the invention, and various changes or modifications may be made by those skilled in the art without departing from the spirit and scope of the invention.

Having fully described my invention, what I claim as new, and desire to secure by Letters Patent, is—

15 1. In filling-detecting mechanism for looms, a filling-fork adapted to be moved by engagement with the filling, and separate, positively-acting means to insure return of the fork to detecting position.

20 2. In filling-detecting mechanism for looms, a movable support, a filling-fork fulcrumed thereon, a vibrating member to coöperate with the fork and thereby move its support upon detection of filling failure, and means whereby said member insures the return of the fork to detecting position.

25 3. In filling-detecting mechanism for looms, a filling-fork adapted to be tilted by engagement with the filling, an extension on the fork tending to balance the same in detecting position, and means adapted to engage said extension and insure return of the fork to detecting position.

30 35 4. In filling-detecting mechanism for looms, a filling-fork adapted to be tilted by engagement with the filling, a depending extension on the fork near to and below its axis, a vibrator, a hook thereon to coöperate with the fork upon detection of filling failure and thereby

effect a change in the operation of the loom, and means to move the tip of the hook upward on the outward stroke of the vibrator and thereby permit free tilting movement of the fork when engaged by the filling, the tip 45 of the hook and the extension coöoperating on the inward stroke, to insure return of the fork to detecting position.

5. A fork-slide having a hook-support, a filling-fork fulcrumed on the slide, a tail to 50 coöperate with the hook upon detection of filling failure, a vibrator, and a connected hook slideable on the hook-support and having a cam portion to ride thereon when the hook moves outward, to elevate the hook and 55 temporarily limit the return movement of the fork after it has been tilted.

6. A fork-slide, a filling-fork carried thereby provided with a tail and adapted to be tilted by engagement with the filling, a vibrating hook having a shoulder and a cam-surface between the shoulder and the tip of the hook, and means to lift the hook on its outward stroke to elevate the cam-surface and thereby 60 limit descent of the fork-tail, to prevent re- 65 bound of the fork.

7. The combination, with a tilttable filling-fork, of a weft-hammer, a hook pivotally connected therewith, and means to lift the hook on the forward stroke of the weft-hammer, to coöperate with and decrease temporarily the return movement of the fork after 70 it has been tilted.

In testimony whereof I have signed my name to this specification in the presence of 75 two subscribing witnesses.

ARTHUR E. BENSON
